UNITED STATES PATENT OFFICE.

EDWARD WANTON SMITH, OF PHILADELPHIA, PENNSYLVANIA.

RETAINING ENVELOP OR COVER FOR STORAGE-BATTERY ELECTRODES.

1,086,864.

Specification of Letters Patent. Patented Feb. 10, 1914.

Application filed July 7, 1911. Serial No. 637,249.

To all whom it may concern:

Be it known that I, EDWARD WANTON SMITH, a citizen of the United States, and a resident of Philadelphia, in the county 5 of Philadelphia and State of Pennsylvania, have invented certain new and useful Improvements in Retaining Envelops or Covers for Storage-Battery Electrodes, of which the following is a specification.

10 The present invention is an improvement upon the envelops or covers forming the subject-matter of an application for a patent serially numbered 636,469, filed on the first day of July 1911 by me jointly with 15 Edward G. Steinmetz, and the principal object of the present invention is to increase the inherent strength and the longitudinal rigidity of the tubes, envelops or covers as a whole and to provide for better holding the minute crevices or pores in 20 proper relation and at the same time to provide the tubes with integral means for spacing the electrodes in respect to each other.

25 The present invention is applicable to the various embodiments illustrated and described in the prior application above referred to, but a preferred embodiment of the present invention is illustrated in the 30 accompanying drawings in which—

Figure 1, is a side view of a blank from which a cover or envelop embodying the present invention is made. Fig. 2, is a cross-section taken on the line 2—2 of Fig. 35 1. Fig. 3, is a side view of a finished cover or envelop embodying features of the present invention, and Fig. 4, is a cross-section taken on the line 4—4 of Fig. 3.

In the drawings 1 is the blank and it consists of an insulating tube having a smooth 40 bore and externally provided with projecting ribs 2 which range or extend longitudinally or generally axially of the tube and project out from the outer surface of 45 the tube. The blank is, as has been said,

of insulating material which should be possessed of the requisite elasticity, strength and non-corrosive or acid resisting properties. Hard rubber is an example of a suitable material from which to make the tube. 50

The tube is provided with minute pores or preferably crevices 3, the width of the pores or crevices being small in comparison with the thickness of the wall. As a matter of description and not of limitation it may be said that for a wall one-thirty second of an inch thick, an elongated opening from two-one hundredths to one-one hundredths of an inch or less in width is appropriate and in any case the width of the opening 55 is less than the thickness of the wall. The pores or crevices 3, as shown, range or run circumferentially between the ribs. The ribs by holding the imperforate portion 4 between the pores or crevices in proper 60 spaced relation insure the proper opening of the pores or crevices. Since the ribs project there is left after the formation of the pores or slots, sufficient cross-section, as at 5, for imparting inherent strength 65 and longitudinal rigidity to the slotted tube for efficiently maintaining the restricted openings 3 under all conditions of manufacture and use. The tube is preferably of cylindrical cross-section. 70

75 What I claim is:

A retaining envelop or cover for storage battery electrodes which comprises an insulating tube having an integral wall provided with longitudinally disposed projecting ribs and elongated minute pores or crevices extending circumferentially between the ribs and held open thereby, said ribs also serving to strengthen the tube and to operate as a spacer. 80

EDWARD WANTON SMITH.
